US00D780025S

(12) **United States Design Patent** (10) **Patent No.:** **US D780,025 S**
(45) **Date of Patent:** **** Feb. 28, 2017**

(54) **RING**

(71) Applicant: **HARRY WINSTON SA,**
Plan-les-Ouates (CH)

(72) Inventor: **Rie Yatsugi-Kang**, Cresskill, NJ (US)

(73) Assignee: **HARRY WINSTON SA,**
Plan-les-Ouates (CH)

(**) Term: **15 Years**

(21) Appl. No.: **29/539,518**

(22) Filed: **Sep. 15, 2015**

(30) **Foreign Application Priority Data**

Mar. 16, 2015 (WO) DM/085885
